US0D1009956S

(12) **United States Design Patent** (10) **Patent No.:** **US D1,009,956 S**
(45) **Date of Patent:** **** Jan. 2, 2024**

(54) **CORE BIT**

(71) Applicant: **Hilti Aktiengesellschaft**, Schaan (IL)

(72) Inventors: **Cliff Toldo**, Vaduz (LI); **Marcel Sonderegger**, Balgach (CH); **Joshua Truschner**, Triesen (LI)

(73) Assignee: **Hilti Aktiengesellschaft**, Schaan (LI)

(**) Term: **15 Years**

(21) Appl. No.: **29/728,922**

(22) Filed: **Mar. 23, 2020**

Related U.S. Application Data

(62) Division of application No. 35/505,298, filed on Jan. 11, 2018 (U.S. filing date under 35 U.S.C. 384), and having an international filing date of Jan. 11, 2018, now Pat. No. Des. 883,350.
